his Attorney.

UNITED STATES PATENT OFFICE.

ARTHUR STEDMAN, OF CINCINNATI, OHIO, ASSIGNOR TO M. A. HUNT & CO.,
OF CINCINNATI, OHIO, A FIRM.

SPRING STRUCTURE.

No. 853,380.

Specification of Letters Patent.

Patented May 14, 1907.

Application filed October 1, 1906. Serial No. 336,879.

To all whom it may concern:

Be it known that I, ARTHUR STEDMAN, a citizen of the United States of America, and a resident of Cincinnati, in the county of Hamilton and State of Ohio, have invented certain new and useful Improvements in Spring Structures, of which the following is a specification.

My invention relates to improvements in spring-structures, more especially to such structures as comprise one or more helical or coil springs having intersecting tie-wires, the latter being provided for the purpose of uniting a number of said coil springs and supporting them in an upright operative position for use in such articles of manufacture as beds, couches and seats, or the like.

My invention consists in an article of manufacture comprising one or more coil springs and tie devices, the latter uniting and supporting the former in an upright operative position and such tie devices being electrically-welded at their several intersections with said coil springs and adapted to form a spring-structure for use in beds, couches and seats.

The accompanying drawing illustrates a diagrammatic plan view of one of the many forms of spring-structure to which my invention herein is adapted.

In said view, 1 indicates each one of a number of coil-springs arranged in parallel rows or series at suitable distances apart for use in such structures as beds, couches and seats, as customary.

2 represents each one of a series of longitudinal tie-wires, and 3 indicates each one of a series of transverse tie-wires, arranged as customary in connection with said coils 1, the respective wires 2 intersecting the respective wires 3 at points 4 concentric to each of said springs 1.

At the various intersections or crossing-points 5 of each of the tie-wires 2 and 3 with

each of the coils 1 an electrically-welded joint is made or effected in any suitable manner, so that said tie-wires are rigidly and firmly bound or connected to said springs without the use of other means. The said tie-wires may be bent or not, as desired, at said intersections with the coils, and the intersections of the tie-wires with each other may or may not be electrically-welded, as desired, at the respective points concentric to the several springs in order to make the structure the more rigid at its joints and of greater stability for use.

It is obvious that other forms of spring-structure than the one shown and above described can be electrically-welded at intersecting points between the tie devices and the springs and I do not wish to be understood as limiting myself to the precise form shown.

I claim:

1. A spring-structure comprising one or more coils and one or more tie-wires or the like intersecting said coils, the intersections between said coils and ties being electrically-welded together.

2. A spring-structure comprising one or more series or rows of coil-springs and intersecting tie-wires, such tie-wires intersecting each other concentric to said coil-springs and the intersecting points between the tie-wires and the coil-springs being electrically-welded together.

3. A spring-structure comprising one or more coils and one or more tie-wires, the latter intersecting the outer ends of said coils and intersecting each other concentric to said coils, and electrically-welded joints at each of said intersections.

ARTHUR STEDMAN.
